MEANS FOR USE IN PRESTRESSING
CONCRETE STRUCTURES

Rudolph Drucker, London, England, assignor to G.K.N.
Reinforcements Limited, Smethwick, England, a British
company

Filed Nov. 2, 1961, Ser. No. 149,704

2 Claims. (Cl. 24—126)

This invention relates to the prestressing of concrete wherein, high tensile steel wires extend longitudinally through a concrete member and have a high tensile stress applied to them which is subsequently transferred to the concrete with the result that the concrete is under compression in the longitudinal direction of the wires. This technique and the advantages thereof, are generally well-known and understood.

The invention is concerned with the case where the tension member comprises a multi-wire strand tension member of the type described and claimed in my co-pending application Serial No. 149,703.

The object of the invention is to provide an improved form of anchorage device for use in holding the ends of multi-wire strands of the type above referred to so that the required tensile stress may be applied.

According to the invention we provide an anchorage device for pre-stressed concrete structures for gripping the ends of drawn wire tension members in contact side by side in at least two rows, the wires in adjacent rows being staggered in relation to each other and in direct contact, and comprising a rectangular outer frame having an opening of rectangular cross-section extending therethrough and co-operating fixed and movable wedge members within said opening to apply a grip to the assembly of the ends of the wires, and wherein two opposed movable wedge member engage directly the outermost faces of the rows of wires and two slidable packing pieces are disposed so as to contact the wires at the ends of the rows, being disposed in between these wires and the adjacent side walls of the outer frame and being engaged with the movable wedge members so as to slide relatively to the frame in unison with the movable wedge members.

The invention is illustrated in the accompanying drawings wherein:

FIGURE 1 is an end view of an anchorage device holding one end of a multi-wire strand tension member.

FIGURE 2 is a section on the line 2—2 of FIGURE 1 the tension member being omitted.

FIGURE 3 is a section on the line 3—3 of FIGURE 2, the tension member being omitted.

FIGURE 4 is a perspective view of a clip for securing together the wires in the tension member.

FIGURE 5 is a diagrammatic illustration of the use of the clip shown in FIGURE 4.

FIGURES 6 and 7 illustrate another form of clip.

Referring to FIGURE 1, the tension member shown there by way of example comprises a plurality of wires all of the same diameter and arranged in three superposed rows the wires in each row being straight and parallel to one another and as shown, there are five wires indicated at 10 in the upper row, four wires at 11 in the middle row and five wires indicated at 12 in the lower row. It will be observed from FIGURE 1 that the cross-section of the multi-wire strand tension member is such that it is bounded by a rectangle.

FIGURE 4 illustrates one form of clip which may be used for securing together the wires in such tension member and this clip is formed from a metal strip 21 which has been bent to form two rows of superposed pockets 22, the pockets in the lower row being staggered in relation to those in the upper row and a consideration of FIGURE 4 will show that the bent form of the strip

2

21 amounts to a series of S bends connected together with adjacent S elements facing in opposite directions.

The wires are received in the pockets 22 and are preferably resiliently gripped therein by forming the complete clip from a suitable metal strip having inherent resilience.

The use of the clip illustrated in FIGURE 5 is applied to the tension member having three superposed rows and it will be observed that the clips are used at spaced 10 positions along the length of the tension member, some of the clips being used to hold the wires 10 and 11 in the upper and middle rows and the other of the clips being used to hold the wires 11 and 12 in the middle and lower rows thus connecting all three rows together.

Another form of clip is shown in FIGURES 6 and 7, the one part of the clip shown in FIGURE 6, being formed from a length of resilient metal strip which is bent to substantially sinusoidal form so as to provide a number of side-by-side pockets 30 each having slots 31 in opposed 20 sides with the portions 32 between the slots being each of substantially semi-circular form. At each end of the strip there is a half portion 32 the edge of which is stepped as shown at 33.

The complete clip shown in FIGURE 7 comprises an 25 exactly similar part inter-engaged with the part shown in FIGURE 6. The wires are placed in the pockets 30 of the clip part A and then clip part B is slid along the wires until its slots 31 interlock with the slots 31 of the part A when it will be observed that the portions 32 of the two 30 parts come together to define substantially circular pockets 34 each containing a wire and then stepped portions 33 at the end of the clip parts are also inter-engaged.

The anchorage device shown in FIGURES 1—3 has an outer casing 14 which is of rectangular cross-section and an opening 15 extending centrally between opposite ends 35 of the outer casing, this opening being of rectangular cross-section. The multi-wire strand tension member as hereinbefore described has a cross-section which is bounded by a rectangle.

Considering the position of the anchorage device shown in the drawings, the upper and lower faces of the rectangular opening 15 through the outer casing 14 are each provided with a fixed wedge member 16 which extends from end-to-end of the casing and is located centrally between the opposed vertical sides of the opening so that on each side of each wedge member 16 there is a clearance gap 17 (see FIGURE 3) between the side face of the wedge member and the adjacent vertical side of the opening 15.

Each movable wedge member 18 is a separate loose wedge member which, when in position, is in wedging engagement in the space between the upper (or lower) face of the multi-wire strand and the adjacent inclined face of the co-operating fixed wedge member 16.

Each movable wedge member 18 is of substantial I 55 form so that at each end it has laterally projecting portions 19, thus providing two elongated gaps one along each side of each wedge member 18 and these gaps are occupied by packing pieces 20 each of which is in the 60 form of a slab of square or rectangular form, each such packing piece 20 being located at its upper edge in the appropriate gap 17 on the side of the upper wedge member 16 and at its lower edge in the similar gap 17 on the adjacent side of the lower wedge member 16. Consequently, when the movable wedge members 18 are forced into wedging engagement to secure the multi-wire strand inside the casing, the two packing pieces 20 also move with the movable wedge members 18 and thus obviate any rubbing contact between the side wires of the multi-wire strand and the adjacent sides of the opening 15 in the outer casing of the anchorage device.

The above described tension member and clips for use therewith, form the subject of my co-pending application Serial No. 149,703.

What I claim then is:

1. An anchorage device for pre-stressed concrete structures for gripping the ends of drawn wire tension members in contact side by side in at least two rows, the wires in adjacent rows being staggered in relation to each other and in direct contact, and comprising a rectangular outer frame having an opening of rectangular cross-section extending therethrough, fixed and movable wedge members within said opening to apply a grip to the assembly of the ends of the wires, and wherein two opposed movable wedge members engage directly the outermost faces of the rows of wires and two slideable packing pieces are disposed so as to contact the wires at the ends of the rows, being disposed in between these wires and the adjacent side walls of the outer frame and being engaged with the movable wedge members so as to slide relatively to the frame in unison with the movable wedge members. 10 15 20

2. An anchorage device according to claim 1 wherein each movable wedge member is of substantially I shape with the packing pieces being accommodated on opposite sides of the movable wedge members in the gaps formed between the projecting ends of the movable wedge members. 5
